UNITED STATES PATENT OFFICE.

WILLIAM J. KENNEY, OF WILMETTE, ILLINOIS, ASSIGNEE TO UNDER-FEED STOKER COMPANY OF AMERICA, OF CHICAGO, ILLINOIS, A CORPORATION OF NEW JERSEY.

UNDERFEED STOKER.

1,207,768.

Specification of Letters Patent. Patented Dec. 12, 1916.

Application filed October 10, 1914. Serial No. 866,027.

To all whom it may concern:

Be it known that I, WILLIAM J. KENNEY, a citizen of the United States, residing at Wilmette, county of Cook, and State of Illinois, have invented a certain new and useful Improvement in Underfeed Stokers, and declare the following to be a full, clear, and exact description of the same, such as will enable others skilled in the art to which it pertains to make and use the same, reference being had to the accompanying drawings, which form a part of this specification.

In underfeed stokers of the self-cleaning type wherein the dead plates on opposite sides of the retort are perforated for the passage of movable dogs and the air to support combustion is introduced under pressure into the chamber beneath the dead plates, it sometimes happens that too much air flows up through the spaces in the dead plates surrounding the dogs, thus causing a reduction in the pressure at the twyer blocks and in the relative amount of air passing through them. It is necessary, however, to cool the dead plates in some manner, the use for this purpose of the air which supports combustion being of course the simplest and most efficient; and the object of the present invention is to provide simple and effective means for permitting the use of the air which supports combustion for cooling the dead plates, without danger of disturbing the best proportions between the air passing through the twyer blocks and that passing through the perforations in the dead plates.

The various features of novelty whereby my invention is characterized will herein-after be pointed out with particularity in the claims; but, for a full understanding of my invention and of its object and advantages, reference may be had to the following detailed description taken in connection with the accompanying drawing, wherein:

Figure 1 is a longitudinal vertical section taken through an underfeed stoker apparatus arranged in accordance with one form of my invention, the section being taken approximately on line 1-1 of Fig. 2; Fig. 2 is a vertical transverse section taken approximately on line 2-2 of Fig. 1; and Fig. 3 is a top plan view of a portion of the stoker, the front wall of the furnace being in section, and parts being broken away.

Referring to the drawing, 1 represents a

furnace having therein one or more retorts, 2, provided with twyer blocks, 3, around their upper edges. Beside the retorts are dead plates, 4, which coöperate therewith to divide the furnace into a lower air chamber and an upper combustion chamber. Lying in openings, 5, in the dead plates are movable dogs, 6, adapted to feed material overflowing thereon from the retort or retorts to a discharge point at the rear. In the arrangement shown the dogs are arranged in rows, those of each row being connected to a bar, 7, which is reciprocated through a suitable connection with a transverse rock shaft, 8. Air under pressure is introduced into the furnace beneath the dead plates, this being conveniently accomplished by connecting this part of the furnace, the air chamber, to the discharge side, 9, of a blower.

All of the parts heretofore described are of old and well known construction and are simply intended as an illustration of a class of existing apparatus.

As I have heretofore explained, in stokers of this kind conditions sometimes arise in which too much of the air escapes into the combustion chamber through the openings in the dead plates and an insufficient amount passes through the twyer blocks. In order to prevent this, I provide means whereby air pressure will be maintained beneath the dead plates so that the air will flow up through the openings and keep the plates cool, while a higher pressure will be maintained at the twyer blocks and thus insure that the desired amount of air will flow through the twyer blocks. Looking at the matter in another way, I provide means for maintaining the usual static pressure in that portion of the air chamber in the vicinity of the i'et ends of the twyer blocks and a smaller but still an appreciable pressure in the vicinity of the dead plates.

I accomplish the above end by placing beneath each dead plate a partition which cuts off from the main portion of the air chamber a section in the immediate vicinity of the dead plate, the partition being perforated so as to let air pass therethrough less rapidly than it would pass through the openings in the dead plates at the pressure in the main portion of the air chamber. In this way the partition serves as a reducing valve which maintains a lower pressure in

the space between it and the dead plate than is found on the other side. The partition may have an opening or openings controlled by a valve or valves so as to make it possible 5 to regulate the difference in pressure between opposite sides thereof.

In the arrangement illustrated, the partitions take the form of sheet metal casings, 10, deep enough to give free play to the 10 operating connections for the dogs. Each casing has a downwardly-projecting part, 11, embracing the corresponding rocker arm, 12, of the cleaning mechanism, and having an opening, 13, in the extreme lower end. 15 The opening, 13, permits ashes to drop down and air to enter. The front end of each casing is made upwardly inclined and is provided with a door, 14, giving access to the interior. In the bottom of each casing, 20 near the rear end, is a sliding door or valve, 15, adapted to be operated by means of a rod, 16, extending to the front of the furnace. The valve or door, 15, permits the casing to be cleaned and also serves as regulating valve for varying the amount of air which can flow through the dead plates.

While I have illustrated and described in detail only a single preferred form of my invention, I do not desire to be limited to 30 the structural details thus illustrated and described; but intend to cover all forms and arrangements which come within the terms employed in the definition of my invention constituting the appended claims.

35 I claim:

1. In combination, a furnace, a retort and

supports beside the same dividing the furnace into an upper combustion chamber and a lower air chamber, twyer blocks on the retort communicating at their inlet ends 40 with said air chamber, said supports having openings therethrough, means for admitting air under pressure to said air chamber, and partitions separating the space proximate to the under side of the supports 45 from the remainder of the chamber, said partitions having openings therethrough, and a manually operated valve for controlling said openings.

2. In combination, a furnace, a retort and 50 supports beside the same dividing the furnace into an upper combustion chamber and a lower air chamber, twyer blocks on the retort communicating at their inlet ends 55 with said air chamber, said supports having openings therethrough, means for admitting air under pressure to said air chamber, and partitions separating the space proximate to the under side of the supports from the remainder of the chamber, said 60 partitions having small openings therein through which air can flow in sufficient quantities to maintain a slight pressure beneath said supports, said partition also having large openings therethrough, and valves 65 for controlling said large openings.

In testimony whereof, I sign this specification in the presence of two witnesses.

WILLIAM J. KENNEY.
